DRAFT RIGGING

Norman B. Akitt, Rochester, N. Y., assignor to
The Symington Company, New York, N. Y., a
corporation of Maryland

Application July 13, 1929, Serial No. 378,147

4 Claims. (Cl. 213—50)

This invention relates to draft rigging for railway rolling stock and more particularly to an improved form of articulated coupler stem and its connection with an associated yoke.

5 The principal object of my invention, generally considered, is to provide an articulated coupler stem of such a size that it may be interchangeably used with a standard horizontal yoke, or a vertical yoke interchangeable with a standard vertical yoke, such a vertical yoke having a hooded front end with the side walls of the hooded portion for that purpose being more widely spaced, the associated parts on the car being designed to correspond.

10 15 Another object of my invention is to provide a swivel butt coupler adapted for connection to the hooded front end of an associated vertical yoke by a horizontal key, the butt of said coupler being of such a size that it may be interchangeably used with a horizontal yoke, the hooded front end of the vertical yoke having its side walls more widely spaced to accommodate the butt of increased width, said yoke and coupler being adapted for use between center or draft 20 25 sills of standard spacing with front draft lugs reduced in width to correspond with the increased distance between the side walls of the hooded portion of the yoke.

30 35 A further object of my invention is to provide a swivel butt coupler connected to the hooded front end of an associated yoke by a horizontal key, the side walls of said hooded end being strengthened by inwardly extending reinforcements around the key slots, and the sides of the coupler shank having corresponding channels to receive said reinforcements upon angling of the coupler.

40 45 A still further object of my invention is to provide a combined striking casting and front draft lug member particularly adapted for use with an interchangeable swivel butt coupler and vertical yoke connected by a horizontal draft key received in corresponding slots in said casting.

50 Other objects and advantages of the invention relating to the particular arrangement and construction of the various parts will become apparent as the description proceeds.

55 Referring to the drawings illustrating my invention, the scope whereof is defined by the appended claims.

Figure 1 is a partial side elevation and partial central longitudinal section of a coupler and associated vertical yoke shown assembled with the

center sills and other parts of the associated underframe.

Figure 2 is a partial plan and partial horizontal sectional view of the coupler, yoke and parts of the underframe shown in Figure 1.

Figure 2a is a partial front end elevational and partial transverse sectional view on the line 2a—2a of Figure 1, looking in the direction of the arrows, with the coupler removed.

Figure 3 is an end elevational view of the combined striking casting, sill tie, and draft lug member shown in Figures 1 and 2 attached to the ends of the center sills, the stem of the associated coupler being diagrammatically illustrated in dot and dash lines.

Figure 4 is a vertical longitudinal sectional view on the line 4—4 of Figure 3 looking in the direction of the arrows.

Figure 5 is a fragmentary plan of the combined casting shown in Figures 3 and 4.

Figure 6 is a view corresponding to Figure 3 but showing a modification.

Figure 7 is a vertical longitudinal sectional view on the line 7—7 of Figure 6 looking in the direction of the arrows.

Figure 8 is a fragmentary plan view of the form of casting shown in Figures 6 and 7.

Referring to the drawings in detail, like parts being designated by like reference characters, and first considering the embodiment of my invention illustrated in Figures 1 to 5 inclusive, there is shown the stem or shank 1 of a swivel butt coupler or one having a two-part or articulated stem. Said stem is connected to the swivel block or articulated portion 2 thereof by means of a pivot pin 3 extending through the shank loops or rearwardly extending flanges or webs 4 and 5 on the coupler and intercalated flanges or webs 6, 7 and 8 on the swivel block. As is usual in swivel butt couplers of the type illustrated, the shank loops 4 and 5 have their rear edges formed cylindrical and coaxial with the apertures 9 therein for receiving the associated pivot pin 3, which edges engage correspondingly curved pocket portions 10 and 11 on the swivel block 2 for transmitting

buffing forces thereto while permitting the desired angling therebetween. The corresponding edges of the flanges 6, 7 and 8 are desirably curved coaxial with the corresponding pin receiving apertures and fit into a correspondingly curved pocket 12 and closely approach correspondingly curved shoulders or flanges 13 and 14 on the shank of the coupler, a slight clearance, however, being desirably provided as illustrated so that the bearing from the transmission of buffing forces is between

the curved edges of the shank loops and the curved walls of the pockets receiving said loops.

Associated with the coupler 1 is a yoke 15, which in the present embodiment, is illustrated as being of the vertical type with a hooded front end so that there are provided side walls 16 and 17, a top wall 18 and a bottom wall 19. In the present embodiment, the walls 18 and 19 are merely extensions of the top and bottom arms of the yoke. The butt of the coupler 1 or swivel block portion 2 thereof preferably fits snugly between the walls 16 and 17 of the yoke and the width of said swivel block is preferably such that it is approximately that normally used with a standard horizontal yoke so that the swivel butt coupler shown may be used interchangeably with a horizontal yoke without undesirable side clearance. Inasmuch as this is greater than the normal distance between the inner surfaces of the side walls of standard vertical yokes, the yoke 15 illustrated has its side walls more widely spaced than with the standard yoke, the dimensions of said yoke, however, being such that it is interchangeable with said standard yoke.

It would be possible to retain the pivot pin 3 from loss or undesired removal by the associated draft key 20 which serves for connecting the coupler and yoke, as well as supporting the parts in proper alignment by passing through registering slots in the coupler, yoke and associated cheek plates or draft lugs 21 and/or sills 22 when said key is in place. This will be clear from considering that said key passes through a correspondingly notched portion 23 in the pin, and thereby would hold the pin in place as long as the pin was unbroken. It will also be clear that when the coupler is associated with the yoke, the walls or arms 18 and 19 of the yoke might overlie and underlie the ends of the pin and thereby hold it in place. In order, however, to hold the pin in place even when the coupler stem 1 is removed from the associated railway vehicle or car, the lower flange or web 8 of the swivel block 2 is desirably provided with a forwardly extending ledge or flange portion 24 underlying the lower end of the pin 3 and preferably engaging a notched portion 25 thereof. For preventing removal of the pin in the other direction, a pair of lugs 26 and 27 are desirably provided respectively disposed forwardly and rearwardly of the pin aperture through the web or flange 7 of the swivel block 2 and extending from the upper surface thereof. Said lugs are provided with registering longitudinal apertures 28 and 29 for receiving a cotter or other retaining means 30. In order to maintain the vertical dimension of the main part of the yoke 15 standard, the forward portions only of the arms 18 and 19 thereof are offset away from each other to accommodate the retaining means 24, 26, 27 and 30. Inasmuch as the retaining means on top and bottom of the swivel block 2 desirably extend a corresponding distance from the corresponding flanges or webs of said swivel block, the amount of offset of the arms 18 and 19 may be equal, thereby providing a symmetrical yoke which may be used with either arm uppermost.

The side loops or walls 16 and 17 of the yoke 15 are desirably strengthened around the slots 31 and 32 by inwardly extending reinforcements 33 and 34, formed by having the inner faces of forward portions of the side walls converge inwardly to approximately the front ends of said slots, for increasing the strength of connection between said coupler and yoke. It will be clear that these reinforcements limit the permissible angling of a coupler shank of usual construction, and therefore the coupler shank of my invention is formed with channels 35 and 36 of a size corresponding with the reinforcements 33 and 34, but offset forwardly from the normal position of the front ends of the yoke slots an amount corresponding approximately with the normal rearward movement of the coupler on buff, whereby they are disposed mainly in the widened portion of the stem, 10 which, as shown most clearly in Fig. 2, has side walls converging rearwardly to the key slot therein, thereby permitting the necessary amount of angling of the coupler stem, particularly when the cushioning mechanism, indicated diagrammatically at 37, is under compression by the stem of the coupler and associated key moving inward between the arms of the yoke further than is illustrated in the drawings, such inward or rearward movement being permitted by the extension 20 of the slots 32 and 68 rearwardly of the normal position of said key.

For holding the cushioning mechanism against rearward movement, a combined backstop and rear draft lug 38 is provided connected between the sills 22, said casting being formed with a pocket 39 for receiving the rear end or looped portion 40 of the yoke. For supporting the yoke, a carrier 41 is desirably provided extending between the sills 22 and connected to the lower flanges 30 thereof in any desired manner as by means of bolts 42. In order to restrain the cushioning mechanism 37 against forward movement when subjected to draft forces, front draft lugs 21 are provided and desirably riveted to the webs of the 35 sills 22, as illustrated particularly in Figure 2. Said draft lugs are decreased in width to correspond with the increased width of the yoke 15 while still being maintained of adequate width to provide the necessary forward abutments for 40 the cushioning mechanism 37 or front follower thereof. Said draft lugs are desirably formed integral with a combined casting 43 comprising a striking portion 44 adapted to engage the horn 45 of the associated coupler, depending side portions 46 preferably strengthened along their front edges by transversely extending flanges or webs 47 and rearwardly extended along the sides of the sill webs 22 where they are connected to said webs as by means of rivets 48, slotted for receiving the 50 associated key 20, and extended inwardly at their rear ends to provide the front draft lugs 21 which are desirably reinforced by forwardly extending tapering ribs above and below the slot 68 which receives the key 20. The lower ends of the lug portions 21 are desirably bent forwardly and downwardly along the lower edge of the casting, as indicated at 21', thereby strengthening the lugs and the casting, said reinforcement tapering to gradually merge into the sides of the casting 60 like the reinforcing portions above and below the key slots. The striking casting portion 44 is desirably formed with a rearwardly extending web 49, the rearmost portion of which is desirably downwardly offset, as indicated at 50, to extend 65 below and be connected with the center sill cover plate 51, the sides of said offset portion being desirably connected to the rear flange portions of the lugs 21 by curved and sloping beading or flanges 50' as shown most clearly in Figures 4 70 and 5. Said striking portion 44 is also preferably reinforced by a plurality of longitudinally disposed webs 52 extending between the striking portion of the casting, the top web 49 and the lower reinforcing flange or web 53.

Connecting the lower ends of the side portions 46 of the casting 43 is a coupler carrier or sill tie portion 54 comprising an upper web 55 and depending flanges 56 preferably integrally connecting the side portions 46, the outer flange 56 preferably being, in effect, a continuation of the flanges 47 on the side portions. In order to permit insertion and removal of the coupler stem 1, the intermediate part of said sill tie portion 54 is preferably downwardly offset, as indicated at 57, an amount sufficient to provide a space between it and the striking portion corresponding with the extreme vertical dimension of the butt of the coupler stem assembled. The side portions of said sill tie are preferably disposed at a slightly higher elevation to form abutments 58 for supporting the associated coupler carrier block 59, said abutments being desirably notched, as indicated at 60, to receive depending lug portions 61 on the carrier block 59 for holding said block in interlocked relation with respect to the casting 43. In order to prevent undesired removal or loss of said block 59, the same is desirably retained in position by a bolt 62 extending entirely through said block and the side portions of the casting 43 and held in place by a head 63 at one end and a castle or other locking nut 64 at the other end.

Referring now to the embodiment of my invention illustrated in Figures 6, 7 and 8, a combined casting 43^a is illustrated which in combination with separable lugs 21^a is interchangeable with the combined casting 43 of the first embodiment. As in the first embodiment, the casting 43^a comprises a striking portion 44^a, the rearwardly extending upper web or shelf portion 49^a downwardly offset, as indicated at 50^a, for connection with the sill cover plate. The shelf or web 49^a and 50^a together with the lower flange 53^a of the striking portion are reinforced by a plurality of vertical webs 52^a, the rear ends of which gradually taper to decrease in depth and finally merge with the web 50^a adjacent the rear edge thereof.

As in the previous embodiment, the side portions 46^a extend downwardly from the striking portion 44^a and are integrally connected by a sill tie portion 54^a preferably of a construction corresponding with the sill tie portion 54 of the first embodiment and supporting a corresponding coupler carrier block 59^a held in place in any desired manner as by means of a corresponding bolt 62^a. The sides 46^a of the casting are provided with rearwardly extending ears 65 adapted for connection to the outer sides of the associated sills 22^a and rearwardly extending bracket portions 66 with outstanding horizontal webs or flanges 67 adapted to underlie and be connected with the lower flanges of said sills 22^a.

The separable draft lugs 21^a are desirably formed with inwardly extending flange portions along their rear edges and, as in the previous embodiment, said flange portions are reinforced by forwardly extending tapering flanges on the upper and lower edges of said castings and bordering the slot 68^a which is adapted for receiving the connecting key. The slotted draft lug castings 21^a are continued forwardly to overlap the ears 65 on the combined striking casting 43^a and continued beneath the striking casting portion and lower flange 53^a thereof, so that they may be connected by common rivets 48^a extending through the side portions 46^a, ears 65, the draft lugs 21^a, and the center sill webs included therebetween, thereby effecting a secure connection

between the parts. As in the previous embodiment, the width of the flanges on the draft lugs 21^a, forming abutments for the cushioning mechanism, are reduced below standard dimensions so as to accommodate the yoke 15, which, as previously explained, is of slightly increased width to accommodate the coupler stem 1 and swivel block 2 of a width corresponding approximately with that used with a horizontal yoke and other Farlow attachments, whereby an interchangeable swivel butt coupler may be employed. Except as specifically described in connection with the present embodiment, the same may correspond approximately with that of the first embodiment.

Referring now to Figure 2, it will be seen that the slots 31 and 32 in the side walls 16 and 17 of the yoke hood terminate, when in normal position, forwardly of the slots in the draft lugs 21, so that when the coupler is subjected to buffing forces it first moves rearwardly until the front end of the slot therein engages the front edge of the key 20, whereupon the key moves rearwardly until the rear edge thereof engages the rear end of the slotted portions in the side walls 16 and 17 of the yoke hood, moving the yoke 25 rearwardly so that the closed or rear end portion 40 thereof moves toward the backstop casting 38, and upon a full closure of the gear only normal clearance may remain therebetween. At the same time, the rear edge portions of the side walls 16 and 17 of the yoke hood move past the rear or stop surfaces of the draft lugs 21. It will, therefore, be seen that, on buff, provision is made not only for relative movements of the coupler with respect to the yoke, but also for 35 relative movement of the yoke with respect to the draft sills, front draft lugs and backstop.

From the foregoing description of my invention taken in connection with the accompanying drawings, it will be seen that I have devised an 40 articulated coupler stem and vertical yoke combination which is an improvement on that described and claimed in my copending application Serial No. 329,503 filed December 31, 1928. In accordance with my present invention, I maintain the swivel block 2 at very near its original width for use with a vertical yoke, as compared with the standard width for use with a horizontal yoke. In this way I am enabled to maintain the radius of the shank loops or flanges 4 50 and 5 at the standard dimension for use with a horizontal yoke and Farlow attachments. I am also enabled to maintain the butt loops or flanges 6, 7 and 8 while limiting the reduction in width of the butt 2 to a figure which may be used with 55 a standard horizontal yoke without undue side clearance. The width of the butt and the thickness of the side walls 16 and 17 of the yoke are so determined that there is still a sufficient distance between the yoke and webs of the sills 22 for front draft lugs 21 of serviceable height and area. The hood of the yoke is so designed that standard coupler pin retaining means are preserved without change, except that the top lugs 26 and 27 receiving the cotter 30 are disposed forwardly and rearwardly of the pin aperture instead of laterally on either side, thereby making it possible to maintain the upper convolution in the arm 18 of minimum width and the same as the downward convolution in the 70 lower arm 19, leaving shoulders on either side of said convolutions, approximately aligned with the corresponding arms of the yoke, as shown most clearly in Fig. 2^a, whereby they are adapted to serve as continuations of the inner surfaces of 75

said yoke arms and guide the stem of the coupler in longitudinal movement. This also makes it possible to use a symmetrical yoke or one which cannot be applied wrong side up. The rear half or looped portion of the yoke may be of standard construction. By reducing the width of the front lugs 21, I am enabled to maintain the shank radius without notching the side walls 16 and 17 of the yoke as described in connection with my application previously referred to. It will be understood that when, in the present application, I refer to parts of "standard", "normal" or "conventional" construction, I mean such parts constructed in accordance with usual railway practice as standardized by the recommended practice of the American Railway Association in effect on the date of filing of this application.

Although I have described preferred forms of my invention, it is to be understood that I do not wish to be limited to the details, as modifications may be made within the spirit and scope of the appended claims.

Having now described my invention, I claim:

- 25 1. In railway draft rigging, in combination, a vertical yoke formed with side walls connecting the side edges of the forward portions of the yoke arms and forming a hooded front, a coupler with a stem received between the side walls of said yoke and the forward portions of said arms and longitudinally movable with respect thereto, said stem having a swivel block pin-connected thereto and formed with means on its top and bottom surfaces for holding said connecting means in place, said holding means extending similar distances above and below said swivel block, the forward portions of the yoke arms above and below said holding means being similarly bulged locally along the longitudinal center line forming grooves open at the forward ends to clear said retaining means, whereby said yoke may be used with either arm up, and coupler guiding shoulders at opposite sides of said grooves.
- 45 2. A yoke having a hooded front formed by two pairs of oppositely disposed walls, one pair forming top and bottom walls of said hooded front and being bulged locally along the longitudinal center line forming grooves open at the forward ends of said walls, coupler guiding shoulders at opposite sides of said grooves, and the other pair of walls forming sides of said

hooded front having elongated slots extending rearwardly from the normal position of the rear edge of an associated draft key, to enable said key to move rearwardly with respect thereto under the action of buffing forces.

3. A yoke having a hooded front formed by two pairs of oppositely disposed walls, one pair forming top and bottom walls of said hooded front and being bulged locally along the longitudinal center line forming grooves open at the forward ends of said walls, and coupler guiding shoulders at opposite sides of said grooves.

4. In railway draft rigging, in combination with draft sills, a vertical yoke comprising upper and lower arms and side walls connecting the forward portions of said arms, a coupler with a stem fitting between said side walls and formed with longitudinal channels on opposite sides, an auxiliary portion, a pin pivotally connecting said stem and auxiliary portion, said stem, auxiliary portion and yoke side walls being slotted, slotted draft lugs connected to the inner faces of said sills and provided with stop shoulders, and a horizontal key extending through the slots in said coupler stem, auxiliary member, side walls and draft lugs, the slots in the draft lugs being elongated rearwardly of the normal position of said key to a greater extent than those in said yoke side walls, the inner faces of said yoke side walls being spaced to clear said auxiliary portion and the forward portions converging rearwardly to provide reinforcements of maximum strength adjacent the front ends of said slots, said coupler stem channels being correspondingly tapered in depth to provide for nesting of the reinforcements therein, the point of maximum depth of said channels being offset forwardly from the normal position of the front ends of the yoke slots an amount corresponding approximately with the normal rearward movement of the coupler with respect to the yoke on buff, so that upon rearward movement of the coupler with respect to the yoke, as provided by the elongation of the slots, and angling of the coupler stem with respect to the auxiliary member, the yoke reinforcement at one side or the other, depending on the direction of angling, is received in the corresponding channel in the coupler stem, thereby allowing for a greater amount of relative angling.

NORMAN B. AKITT.
